UNITED STATES PATENT OFFICE.

ISAAC SCOTT, OF CHRISMAN, ILLINOIS.

GRAVE-BOX COVER.

SPECIFICATION forming part of Letters Patent No. 486,943, dated November 29, 1892.

Application filed May 27, 1892. Serial No. 434,549. (No model.)

To all whom it may concern:

Be it known that I, ISAAC SCOTT, a citizen of the United States, residing at Chrisman, in the county of Edgar and State of Illinois, have invented a new and useful Grave-Box Cover, of which the following is a specification.

This invention relates to certain new and useful improvements in grave-box covers; and it consists of the construction and arrangement of parts thereof, together with the formation of the bed or brickwork of the grave, as will be more fully hereinafter described and claimed.

15 The object of this invention is to provide an adjustable cover for the top portion of rough boxes to prevent water from flowing upon the same, the said cover being of such construction as to deflect the water to one 20 side away from the rough box and thereby obviate decay of the said box.

In the drawings, Figure 1 is a sectional perspective view showing the improved cover applied in connection with the brickwork of 25 the bottom of the grave. Fig. 2 is a detail perspective view of the improved cover detached.

Similar numerals are employed to indicate corresponding parts in the several views.

30 Referring to the drawings, the numeral 1 designates the side and end walls of brick-work usually constructed at the bottom portion of a grave; but in this special instance one course of brick is left projecting above 35 the upper level of the wall at the inner portion thereof, as at 2, and upon which the improved device is adapted to be applied.

The invention primarily embodies two semicircular metallic plates 3 and 4, telescopically fitted to each other, and having right-angular side flanges 5 which are adapted to rest upon the interior elevated course of brick, as at 2. The said cover is closed at the opposite ends, as at 4^x, and is adapted to be supplied with suitable rings or eyes 6 for lifting or properly positioning the said cover. It will be understood that the rough box will be placed inside of the opening bordered by the elevated course of brick hereinbefore referred 45 to, and when the flanges 5 are resting on said elevated course of brick entrance of water to the rough box will be obviated and will be

shed or deflected to the top portion of the brick wall and flow off therefrom. It will be seen that the interior course of brick is elevated 55 position, as set forth, together with the walls of the grave, will form a sort of gutter or channel for the water running off of the cover, and by this means the rough box will be protected. The cover is made semicircular in form, or approximately so, in order to provide a watershed, as will be readily understood.

The device will be made in various sizes and widths; but for ordinary purposes one cover may be adjusted to various lengths of 65 the grave, as will be readily understood, and thereby avoid the necessity of manufacturing a great number of sizes. In some instances, however, the provision of various widths of cover will be necessary.

70 It will be understood that the cover may be made of any suitable metal; but galvanized iron or analogous material will be preferable by reason of the fact that it does not become so readily corroded by the action of water.

The device is exceedingly durable and will last a great length of time, and aside from the advantage set forth it will be very beneficial in supporting the earth and prevent caving in of the grave.

75 Having thus described my invention, what I claim, and desire to secure by Letters Patent, is—

1. A grave-box cover consisting of two semicircular plates telescopically overlapping each 85 other and having horizontally-positioned side flanges at right angles thereto and vertically-disposed closed outer ends and eyes or rings on the top adjacent to the outer closed ends of each of the plates for lifting the device entire, substantially as described.

2. The combination, with a grave-wall having an inner raised course of brick or stone, of a cover constructed of semicircular plates telescopically fitted to each other and having 95 flanges adapted to rest on said raised course of brick, substantially as described.

In testimony that I claim the foregoing as my own I have hereto affixed my signature in the presence of two witnesses.

ISAAC SCOTT.
